UNITED STATES PATENT OFFICE.

SALI SIMON, OF NEW YORK, N. Y.

DESIGN FOR SHELF-PAPER.

Specification forming part of Design No. 6,766, dated July 8, 1873; application filed June 16, 1873.

A.

To all whom it may concern:

Be it known that I, SALI SIMON, of the city, county, and State of New York, have invented a Design for Shelf-Paper, used to ornament the edges of shelves, of which the following is a specification:

The nature of my design is fully represented in the accompanying drawing, to which reference is made.

A A indicate four trefoil leaves arranged in pairs of opposites, and delineated on the paper by a series of adjacent perforations. In

each leaf there is a star, S. The scalloped edge forms no part of the design. Two of the leaves, those which extend laterally, have stems on them, and among them all is a central hole or perforation.

What I claim as my invention is—

The design for shelf-paper, substantially as shown and described.

SALI SIMON.
